DESIGN FOR A BRASSIÈRE

Roger Emile Casalis de Pury, Earls Court, London, England, assignor to The Charnaux Patent Corset Company Limited, London, England

Application September 17, 1935, Serial No. 58,603
In Great Britain May 23, 1935

Term of patent 14 years

To all whom it may concern:

Be it known that I, Roger Emile Casalis de Pury, a subject of the King of Great Britain, residing at 33 Tregunter Road, Earls Court, London, England, have invented a new, original, and ornamental Design for a Brassière, of which the following is a specification, reference being had to the accompanying drawing, forming part thereof.

The figure is a plan view of a brassière laid out flatly showing my new design.

I claim:

The ornamental design for a brassière, as shown.

ROGER EMILE CASALIS DE PURY.
